Primary Examiner—Alan P. Douglas*Assistant Examiner*—Cathron B. Matta*Attorney, Agent, or Firm*—Barrigar & Moss**[57] CLAIM**

The ornamental design for a planter for mounting on railing, as shown and described.

DESCRIPTION

FIG. 1 is a front perspective view of a first embodiment of the planter of the present invention, which view also shows the top of the planter;

FIG. 2 is another perspective view of the planter of FIG. 1 showing the bottom and left side thereof;

FIG. 3 is a top view of the first embodiment;

FIG. 4 is a bottom view of the first embodiment;

FIG. 5 is a front view of the first embodiment;

FIG. 6 is a side elevational view of the first embodiment;

FIG. 7 is a front perspective view similar to FIG. 1 but showing a second embodiment of the planter of the present invention;

FIG. 8 is a perspective view similar to FIG. 2 but showing the second embodiment;

FIG. 9 is a top view of the second embodiment;

FIG. 10 is a bottom view of the second embodiment;

FIG. 11 is a front view of the second embodiment; and,

FIG. 12 is a side elevational view of the second embodiment.
